UNITED STATES PATENT OFFICE.

HARRY V. HAIGHT, OF SHERBROOKE, QUEBEC, CANADA, ASSIGNOR TO INGERSOLL-RAND COMPANY, OF JERSEY CITY, NEW JERSEY, A CORPORATION OF NEW JERSEY.

PERCUSSIVE-TOOL.

1,391,628.

Specification of Letters Patent. Patented Sept. 20, 1921.

Application filed December 17, 1918. Serial No. 267,186.

To all whom it may concern:

Be it known that I, HARRY V. HAIGHT, a subject of the King of Great Britain, residing at Sherbrooke, in the Province of Quebec, Dominion of Canada, have invented a certain new and useful Improvement in Percussive-Tools, of which the following is a specification.

This invention relates to percussive tools and in particular to a fluid operated percussive or hammer drill admitting a part of the actuating fluid and also a cleansing fluid down the drill steel to free the drill bit from cuttings.

15 The objects of the present invention are to provide a mechanism for controlling the admission of cleansing fluid as well as a part of the actuating fluid to the drill steel from the tool to force the cuttings away from the cutting edges of the drill steel; to provide mechanism wholly contained within the drill for accomplishing this function, the mechanism being operatively controlled by movement of a single means.

20 With the above and other objects in view my invention consists in the features of construction and operation set forth in the following specification and illustrated in the accompanying drawings, forming a part 30 hereof, in which:

Figure 1 shows a longitudinal view of the drill in section;

Fig. 2, a partial longitudinal view taken through another section;

35 Fig. 3, a sectional view of a slight modification, and

Fig. 4 is a transverse sectional view on line 4—4 of Fig. 1 looking in the direction of the arrows.

40 Referring more particularly to the drawings, 1 refers to the cylinder having attached at its forward end a front head 2 within which is contained an anvil block 3. A chuck 4 is provided fitted against the forward end of front head 2 within which is contained the drill steel 5. At the rear end of the cylinder 1 is provided a back head 6 within which is contained the throttle valve 7 controlling the supply of motive and cleansing fluid.

45 In rear of the back head 6 is the feed cylinder 8 of the usual form found in stoppers supplied with fluid through a conduit 9 extending from the throttle 7. As is usual in this type of tool the front head, cylinder, back head, and feed cylinder are held

rigidly together by side bolts, not shown. Within the cylinder 1 operates a piston or hammer 10 at the forward end of its stroke striking the anvil block 3. The piston is of the usual form so will not be further described. Extending forwardly from the throttle valve 7 through the cylinder 1 is a passage 11 joining a continuing passage 12 within the front head terminating in connected grooves 13 provided in the annular inside surface of the front head 2. The function of the grooves 13 is to form an air seal around the anvil block to prevent the passage of the water in either direction from the water groove 21, and the motive fluid 70 pressure maintained in the sealing grooves 13 should be greater than the pressure of the water in the water groove 21. The passage 11 at its rear end joins the throttle valve 7 in a position to intercept passage 14 75 and radial opening 15 provided within the throttle valve 7 which are directly in communication with the source of fluid supply. Another passage 16 extends longitudinally of the cylinder 1 intercepting a short passage 17 within the back head 6 which intercepts a portion of the throttle valve 7 in which is contained an opening 18 in communication, when in its open position, with a water connection 19. The forward end of 80 the passage 16 joins a passage 20 through the front head 3 terminating in the annular groove 21 so that a continuous passage is provided within the tool for water to be admitted to the anvil block. The anvil block 90 3 is provided with passages 22 and 23 intercepting respectively the air and water passages 12 and 20 provided within the front head which intercept each other and extend to the front end of the anvil block in a 95 single passage 24. The passage 24 is central of the anvil block 3 and is directly in alignment with the central hole provided within the drill steel 5.

In the modification shown in Fig. 3 the motive fluid supplied to the anvil block to force the cleansing fluid down the drill steel is taken directly from the front end of the cylinder 1 through a passage 25. This passage 25 is in communication with two annular grooves 26 which are in every way similar to the grooves 13 shown in Fig. 1. From the rearward groove 26 the fluid passes through passages 27 and 28 to the passage 29 in which the motive fluid and 110

cleansing fluid commingle and pass into the drill steel 5. The water nipple in this modification is attached at one side of the front head 2 as shown at 30, communicating with 5 the passage 29 by means of a groove 31 provided in the front head and passage 32 provided in the anvil block.

From the above description it will be seen that a construction has been provided permitting 10 cleansing fluid to be admitted to the anvil block of the drill and from there into the drill steel from a source of supply controlled by a valve preferably located at the rear end of the drill; but as shown in 15 Fig. 3 the source of supply may be located near the front head of the tool. Also, a passage is provided for fluid under pressure to be admitted to the anvil block to aid the forcing of cleansing fluid down the 20 drill steel. Both of these passages are controlled by but one throttle handle in the preferred construction, movement of which first opens the passage 11 to admit motive fluid to the anvil block, after which continued 25 movement of the throttle serves to open passage 16 to admit the cleansing fluid.

It is to be understood that the present showing and description disclose only certain specific embodiments of my present invention, and that other forms and modifications are included within the spirit and scope of the invention, as expressed in the appended claims.

What I claim is:

- 35 1. In a percussive tool, a front head construction comprising a front head, an anvil block slidably mounted therein, a water conduit leading through the side of the front head and the side of the anvil block to a point intermediate the length of said anvil block in a central passage extending to the forward end of the anvil block, for conducting water from the water conduit through the anvil block to a hollow drill steel, and 40 means for producing currents of motive fluid under pressure flowing toward the water connection from each side of the water connection between the anvil block and front head, to prevent the water from 45 passing in counter directions.
- 50 2. In a percussive tool, a front head construction including two members, one a front head and the other an anvil block slidably mounted therein, an annular water 55 groove in one of said members surrounding

said anvil block intermediate of its length, a passage through the side of the anvil block for connecting the said water groove with a central passage extending to the forward end of the anvil block for conducting water 60 to a hollow drill steel, a water conduit leading through the side of the front head to said water groove, one of said members having annular sealing grooves at each side of said water groove, and means for supplying motive fluid under pressure to said sealing grooves to prevent water from passing in either direction from said water groove between the anvil block and the front head. 65

3. In a percussive tool, a front head construction, comprising a front head, an anvil block slidably mounted therein, an annular groove surrounding said anvil block intermediate of its length, a passage through the side of the anvil block for connecting the 70 said water groove with a central passage extending to the forward end of the anvil block for conducting water to a hollow drill steel, a water conduit leading through the side of the front head to said water groove, annular sealing grooves in said anvil block 75 at each side of said water groove, and means for supplying motive fluid under pressure to said sealing grooves to prevent water from passing in either direction from said water groove between the anvil block and the front head. 80

4. In a percussive tool, a front head construction, comprising a front head, an anvil block slidably mounted therein, an annular 90 groove surrounding said anvil block intermediate of its length, a passage through the side of the anvil block for connecting the said water groove with a central passage extending to the forward end of the anvil block for conducting water to a hollow drill steel, a water conduit leading through the side of the front head to said water groove, annular sealing grooves in said anvil block 95 at each side of said water groove, and means for maintaining motive fluid in said sealing grooves under higher pressure than the water contained in the water groove to prevent water from passing in either direction from said water groove between the anvil block and front head. 100

In testimony whereof I have hereunto set my hand.

HARRY V. HAIGHT.
